UNITED STATES PATENT OFFICE.

WILHELM HEINRICH AND FRIEDRICH JANSSEN, OF GEESTEMÜNDE, GERMANY.

LIFE-BUOY.

1,165,503.

Specification of Letters Patent. Patented Dec. 28, 1915.

Application filed December 9, 1913. Serial No. 805,636.

To all whom it may concern:

Be it known that we, WILHELM HEINRICH and FRIEDRICH JANSSEN, subjects of the King of Prussia, and residents of Geestemünde, Germany, have invented certain new and useful Improvements in Life-Buoys, of which the following is a specification.

This invention relates to an improved life-buoy, which is represented on the accompanying drawing, in which—

Figure 1 is a vertical section, Fig. 2 a front view, and Fig. 3 a cross-section on the line I—I of Fig. 1, of the same.

Foldable life-buoys are already known, the same being however made to fit the human body and provided with separate means for insuring the buoyancy. Such life-buoys have the drawback that they are thrown to and fro at rough sea and that, owing to the violent movement, the person in the life-buoy soon loses consciousness. Further, such life-buoys are not at once ready for use and have the inconvenience of deficient or no supply of air.

The improved life-buoy forming the subject matter of the present invention consists of a hollow tank, which in its interior is fitted with a receptacle for drinkable water and which is perforated, a telescopic canvas envelop, which is strengthened by rings, being arranged on said tank and forming, when drawn-out, the life-buoy proper, for which purpose a cover, which can be closed from inside, is fixed thereon.

A further improvement consists in the provision of a pipe on the hood or cover of the life-buoy, the latter being preferably provided with a window or bull's eye, while the upper end of said pipe terminates in a perforated shell which is fixed in any appropriate way, so that through the latter an escape of the bad air and admission of fresh air is allowed.

Another improvement is that the receptacle for drinkable water is provided with a rising-pipe, which is fitted with a stop-cock, through which the water can be sucked by the user of the life-buoy.

Finally, the life-buoy is provided with outer sleeves for the reception of the arms of the user, so that the latter can exert a rowing movement for a propulsion of the life-buoy.

The life-buoy comprises a telescopic canvas envelop *a*, which is strengthened by rings *b* and which can be drawn out by

means of telescopic rods *c*. At the lower end, the canvas envelop is watertightly fixed on a tank *d*, which is provided with perforations *e*. In the interior of the tank, the receptacle *f* for drinkable water is arranged, to which the pipe *g* is attached, to the upper end of which a stop-cock *h* is fixed, so that the user of the life-buoy can suck the water therethrough. At the top, the life-buoy is closed by a bonnet *i*, which consists also of canvas and which carries a window or bull's eye *k* which can be closed from inside. At the highest point of the bonnet *i* a pipe *l* is arranged, on the end of which a shell *m* is put, which is provided with holes *n*. The pipe may at the same time serve for fixing a distress-flag *o* thereto. The hood *i* is closed from inside by pivotal screw-bolts *p*. In the interior of the life-buoy, preferably a food-bag *q* is arranged. The life-buoy carries further lateral sleeves *r* of flexible material, for instance canvas, leather or the like, which can be drawn inward, if for instance a shark does approach the life-buoy. Preferably, outer ropes *s* serving as handles are arranged on the life-buoy, so that the same can be dragged along by means of a drawing-rope *t*.

By the improved construction, the life-buoy can be at once put ready for use. On boats, particularly on fishing-boats, which frequently sink within a few minutes after an accident, a large number of such life-buoys can be easily arranged. The wrecked person needs to stand on the tank only, pull the telescopic canvas envelop upward, quickly close the upper hood and jump over board. By the tank being still empty, the user can quickly move forward with the life-buoy by jumping movements. For this purpose, straps *u* are arranged on top of the tank for the reception of the feet. Upon the life-buoy being in the sea, the tank is quickly filled with water so that the gravity of the life-buoy lies at the lower end of the same whereby a to and fro throwing of the life-buoy by rough sea is prevented.

The drawing-rope *t* is preferably permanently fixed to the life-buoy, so that the wrecked person can fix the same through the bull's eye *k* to a rope thrown from a passing ship. A suspension-hook *x* may be provided on the outside of the life-buoy for suspension of the same from the board of the wreck, whereupon the wrecked person enters the life-buoy and need then only dis-

engage the hook from the board by an upwardly jumping movement assisted by manipulation through the bull's eye *k*, so that the life-buoy falls directly into the sea. By the arrangement of the outer ropes *s* which serve as handles, a number of persons can be farther saved without entering the life-buoy by catching said handles from outside.

What we claim, is:

10 A life-buoy, comprising in combination, a perforated tank, a telescopic canvas envelop upon said tank, rings to strengthen said envelop, an upper hood on said en-

velop adapted to be closed from inside, a receptacle for drinkable water in said tank, 15 a rising-pipe on said receptacle, and a stop-cock on top of said pipe, substantially as and for the purpose set forth.

In testimony whereof we have hereunto set our hands in the presence of two subscribing 20 witnesses.

WILHELM HEINRICH.
FRIEDRICH JANSEN.
